CLAIM

The ornamental design for a camera body, as shown and described.

DESCRIPTION

FIG. 1 is a top, front and side perspective view of a camera body showing our new design;

FIG. 2 is a front elevational view thereof;

FIG. 3 is a view similar to FIG. 1, but with the parts in a different position; and,

FIG. 4 is a top, front and side perspective view thereof, the broken line showing of a lens body and camera housing are included to illustrate the environment only and forms no part of the claimed design.

The portions of the camera body in broken lines are shown for illustrative purposes only and form no part of the claimed design.
